UNITED STATES PATENT OFFICE.

LEWIS L. WOMACK, OF ZEPHYR, TEXAS.

COTTON-STALK PULLER.

SPECIFICATION forming part of Letters Patent No. 446,276, dated February 10, 1891.

Application filed September 2, 1890. Serial No. 363,797. (No model.)

To all whom it may concern:

Be it known that I, LEWIS L. WOMACK, of Zephyr, in the county of Brown and State of Texas, have invented a new and useful Improvement in Cotton-Stalk Pullers, of which the following is a specification.

My invention is an improved machine for pulling cotton-stalks from the ground, and has for an object to provide a machine simple of construction, easy of operation, and efficient in use.

The invention consists in certain novel constructions and combinations of parts, as will be hereinafter described, and pointed out in the claims.

In the drawings, Figure 1 is a top plan view, Fig. 2 is a sectional side view, and Fig. 3 is a sectional front elevation, of my machine; and Fig. 4 is a detail sectional view of the pulling-wheel and the constructions for supporting the same.

The axle A is journaled in the main frame B and has one or both wheels C secured to it, so that the axle will be turned as the implement is moved along the ground. Below the axle A the main frame is provided with a bar D, extended in line with the axle and provided centrally with a bearing d for the upper end of the shaft of the pulling-wheel. By preference this bar D is fixed at its ends to the under sides of the boxes b, in which the shaft A journals. A hanging frame E is also supported on the main frame and consists of the base-plate F and the rods G, which extend from the corners of the base-plate F to the corners of the main frame and support the plate G rigidly in position below the axle.

In the plate F is formed a bearing f, arranged vertically below the bearing d in bar D. The arrangement of the supporting-rods G is such that a wide space is provided within the frame E immediately below the bar D, in which the large horizontal gear presently described may operate.

The shaft H of the pulling-wheel I has a shoulder h, which rests on the plate F, a round portion J below such shoulder, which journals in bearing f, and a squared portion K below part J. This portion K receives the wheel I and has a series of perforations k for a pin L, which is arranged below the said wheel I and may be adjusted into one or the other

opening k to hold the wheel at different heights. Above the shoulder h the shaft H is squared to receive the large gear-wheel M, which is arranged to operate immediately below the bar D. At its upper end the shaft H is rounded and fits and turns in the bearing d of bar D.

The wheel M is meshed by a pinion m on the axle A, said pinion being arranged at the left side of the wheel M, so that as the implement moves forward the wheel M, its shaft, and the attached pulling-wheel will be turned from right to left, the direction of motion of the pulling-wheel being relative to the inclination of the pulling-pins, as hereinafter described.

The pulling-wheel I is formed with a dish or concave rounding up toward its center, where it is secured on the shaft H in the manner before described. I make this wheel with spokes O and a rim P, the latter being mortised out at p to form seats for the pins or teeth Q, which fit at their inner ends in the said seats and are secured by bolts, as shown. The seats p are formed and arranged to secure the pins or teeth approximately at a tangent to the frame or main portion of the wheel, so that the teeth will project at a tangent and operate to receive the stalks as the machine moves along the row. The spaces between the teeth and the rim of the wheel receive the stalks and the said spaces open rearwardly with respect to the direction in which the wheel is turned.

As shown by the arrow, the pulling-wheel is turned in a direction to cause its side engaging the cotton-stalks to move rearwardly or in a direction opposite to that in which the machine is advancing. The wheel operates to pull the stalks by reason of the difference between the speed at which the wheel is turned and that at which it is moved over the ground, the wheel being moved forward at a faster speed than it turns back, so that as the stalks are caught by the teeth they will be pulled forward out of the ground, and as the wheel turns back they will be carried back to a point in rear of the machine, where they will be discharged, the discharging of the stalks being made certain by means of a discharging-bar R, secured at one end to the hanging frame E and arranged at its other

end to project over the wheel above the teeth and to force the stalks out of the space between the pin and wheel-rim, and so clear the wheel. The tongue is secured to the main frame 5 about in line with the rearwardly-moving side of the pulling-wheel, so as to place the draft in the direction of greatest strain, and the doubletree is placed below the tongue, in order to exert a lifting tendency on the main 10 frame and the parts supported below the same.

Having thus described my invention, what I claim as new is—

1. In a stalk-puller, a pulling-wheel having its rim formed with seats *p* for the inner ends 15 of the pins *Q*, the pins *Q*, fitted at their inner ends in said seats and projecting at their outer ends at a tangent, and the fastenings by which to secure the pins to the wheel, substantially as and for the purposes set forth.
20. 2. In a stalk-puller, the combination of the axle and main frame, the pulling-wheel having its rim provided with tangentially-projected

pins, and means for revolving said wheel as the puller advances over the ground, the pulling-wheel being turned to move rearwardly 25 on its side, engaging the row as the puller advances, all substantially as and for the purposes set forth.

3. In a stalk-puller, the combination of the shaft *H*, having perforations *k*, the pulling-wheel *N*, dished upward toward the center, fitted at the center on the shaft *H*, and provided at its rim with pins *Q*, and the pins *L*, by which the wheel *N* may be secured at different heights, all substantially as and for 30 the purposes set forth.

35. 4. In a machine substantially as described, a pulling-wheel provided at its rim with tangentially-projected pulling-pins, substantially as set forth.

LEWIS L. WOMACK.
